UNITED STATES PATENT OFFICE.

CHARLES W. MEADOWCROFT, SR., OF PHILADELPHIA, PENNSYLVANIA.

PNEUMATIC TOOL.

No. 853,416.

Specification of Letters Patent.

Patented May 14, 1907.

Application filed December 26, 1906. Serial No. 349,421.

To all whom it may concern:

Be it known that I, CHARLES W. MEADOWCROFT, Sr., a citizen of the United States, residing at Frankford, in the city and county of Philadelphia and State of Pennsylvania, have invented certain new and useful Improvements in Pneumatic Tools, which improvements are fully set forth in the following specification.

10 This invention relates to improvements in devices of that class commonly known as pneumatic tools, the same being utilized for delivering, in rapid succession, a multiplicity of sharp, powerful blows, wherever needed, 15 as in the operation of riveting, chiseling hard objects, as stone, and the like.

20 The object of this invention is to provide a tool of the character above indicated which, by reason of its marked simplicity and novelty in details of construction, and the reduction 25 in number of its operating parts to a minimum, may be conveniently and cheaply manufactured, as for commercial purposes; which shall embody compound features of 30 construction, including a reciprocating striking-piston of maximum effective area, thereby materially enhancing the efficiency of the tool as a whole; which shall be durable, positive in operation, and ordinarily suitable for 35 hand-manipulation on the part of the user; and which shall possess certain well-defined advantages over prior analogous devices.

35 The invention consists in the novel combinations, parts and details of construction whereby, together with the novel disposition and relative arrangement of said parts, the attainment of the foregoing object is rendered practicable, all of which will be herein-after more specifically described and set forth 40 in the appended claims.

45 The invention is clearly illustrated in the accompanying drawings, wherein like reference-numerals denote corresponding parts throughout the several views, and as to the latter:

Figure 1 is a side elevation of a pneumatic tool embodying my said improvements, a portion of the wall of the casing or main cylinder thereof being broken away to disclose 50 certain interior details, and particularly the reciprocating striking-piston therein under reverse adjustment. Fig. 2 is a central, longitudinal section of the device, the striking-piston being shown in the position it occupies under direct adjustment, as for a striking effect, and partly in section to disclose 55

certain details interior thereof. Fig. 3 is a front end view of the construction shown in Fig. 1. Fig. 4 is a view in perspective of the reciprocating, striking-piston, detached from the general construction. Fig. 5 is a detail sectional view, showing detached from the general construction, the subsidiary cylinder made use of, the section being taken centrally and longitudinally thereof. Fig. 6 is an end view of said subsidiary cylinder.

In a general sense my present invention comprises a main casing or cylinder; a subsidiary cylinder fixed within the main cylinder, forming a distribution chamber, and 70 having opposing inlet ports whereby, respectively, communication is established between said distribution chamber and the interior of said main cylinder, the latter having a main, power-medium supply-passage communicating primarily with said distribution chamber, and suitable, opposing exhaust ports; and a compound, reciprocating, striking-piston, the latter, in its reciprocating movements, controlling alternately said opposing inlet 75 ports and said opposing exhaust ports, and inversely the inlet ports with respect to the exhaust ports, or vice versa, and being movable under the introduction to and exhaustion from said main cylinder, accordingly, of 80 a power-fluid, preferably air under pressure, at opposite sides thereof.

Having reference to the accompanying drawings, 2 denotes a main casing or cylinder, the front portion of whose bore is enlarged 90 and threaded to receive a tubular chuck or nose-piece 3, the latter being shouldered and threaded to this end, substantially as indicated in the drawings. Said main cylinder is further provided, at its rear end, with a 95 nozzle 4, interiorly threaded to receive the end of a flexible tube, or other appropriate connection, whereby, and by way of the supply-passage 5, with which said main cylinder is provided, a suitable power-medium, 100 preferably air under pressure, may be conducted from any appropriate source of supply and delivered to and into the distribution chamber 6, situated within the main cylinder 2.

105 7 denotes a subsidiary cylinder, firmly disposed medially within the main cylinder 2, and cut away centrally and circumferentially thereof, substantially as shown in the drawings, to form when thus in place and with the 110 adjacent wall of the cylinder 2, the distribution chamber 6 aforesigned; and I prefer

that said subsidiary cylinder be cut away wholly circumferentially, thereby giving to said chamber an annular form and accordingly rendering it co-extensive with the circumference of said subsidiary cylinder, the latter being provided with a primary inlet port 8 and a secondary inlet port 9, by way of each of which communication is established between the distribution chamber 6 and the interior of the main cylinder 2.

I further make use of a compound, reciprocating, striking-piston, enlarged diametrically midway its length to form a valve-shoulder 10, which fits snugly and operates to and fro within, the subsidiary cylinder 7, and hence serves in its reciprocating movements, to alternately open and close, and accordingly control, the inlet ports 8 and 9. Said piston is further provided with opposite working-heads 11, 12, situated, respectively, a suitable distance from, and at opposite sides of, the valve-shoulder 10, and fitting neatly, respectively, the bore of the main cylinder 2, thereby forming the compound, primary expansion chambers 13, 14, which essentially intercommunicate, and preferably by way of an axial passage 15, intersected by one or more lateral passages 16, all here shown as being formed in said piston, though the same may be otherwise arranged, as in the wall of the chamber 2, in practice. The head 12, fitting snugly in the bore of the cylinder 2, and the valve-shoulder 10, fitting snugly in the subsidiary cylinder 7, form, between them, a secondary expansion chamber 17.

The main cylinder 2 is provided with a primary exhaust port 18, for the exhaust from the chamber 14, and with a secondary exhaust port 19, for the exhaust from the chamber 17, both of said exhaust ports being here shown as communicating with a common exhaust passage 20, formed in the wall of the main cylinder 2, extending rearwardly therealong, and terminating in a general exhaust port 21, at the rear end of the main cylinder 2.

Exhaust ports 18 and 19 are alternately opened and closed and hence accordingly controlled, by the piston-head 12, under the reciprocating movements of the latter, and inversely to the opening and closing of the inlet ports 8 and 9 by the valve-shoulder 10; that is, said valve-shoulder and the piston-head 12 bear such relation, in their disposition, each to the other, that when the former opens the primary inlet-port and accordingly closes the secondary inlet-port, the latter, said piston-head, opens the secondary exhaust port and closes the primary exhaust port, the piston, as a whole, occupying, under such conditions, substantially the position indicated in Fig. 1 of the drawings; and when valve-shoulder 10 shall have opened the secondary inlet-port, as 9, and closed the

primary inlet-port, as 8, the piston-head 12 will have opened the primary exhaust port, as 18, and closed the secondary exhaust port, as 17, the piston as a whole, having moved into substantially the position indicated in Fig. 2 of the drawings, and which alternate opening and closing of the respective inlet-ports and the respective exhaust ports, and the control of said inlet-ports inversely, as stated, with respect to the exhaust ports, or vice versa, normally continues under the reciprocating action of said piston. Hence, in my improved pneumatic tool the use of valves, as distinct operative parts, for controlling the respective inlet and exhaust ports, is obviated, the construction as a whole being accordingly much simplified, and the cost of producing it being much reduced.

It will be understood that a plurality of inlet-ports, arranged as primary and secondary, and substantially as indicated in the drawings, may be availed of at suitable intervals circumferentially of the subsidiary cylinder 7; and this applies, also, to the exhaust ports 17 and 18 with respect to the main cylinder 2.

The threaded opening at the nozzle 4 may be reduced, continued inwardly and threaded, to permit access to the interior of the cylinder 2 for any required purpose, as for forcing out or removing the subsidiary cylinder 7, the latter being inserted in place within the cylinder 2 under strong pressure; and a threaded plug, as 22, or other appropriate device, may be availed of for normally closing the continued portion of said opening, said plug having a squared, or otherwise suitably shaped recess at its outer end, and as indicated in dotted lines in Fig. 2, to facilitate adjustment of said plug as may be required.

To facilitate the adjustment of the subsidiary cylinder 7, relatively with respect to the striking piston aforesaid, the same may be formed in two or more segments, as indicated in Figs. 5 and 6. The striking-piston aforesaid is provided at its front end with a striker 23, adapted, at each forward thrust of said piston, to impinge upon and deliver a powerful blow to, any appropriate object, as a rivet, or the shank, as 24, of a working tool, as a chisel. However, where the object to be acted upon is the shank, as 24, of a working tool, it is desirable that means be provided whereby the same may be loosely held in axial alinement with said striker, and in position to receive blows from the latter; and to this end I provide the chuck or nose-piece 3, aforesaid, the same, by preference, taking the general character of a cylinder open at both ends, and the main outer portion of whose bore is somewhat larger in diameter than the shank of the tool to be acted upon, and is reduced somewhat near its inner end to form a shoulder 25, against which, in practice, the adjacent end

of the tool-shank may abut, all as clearly illustrated in Fig. 2 of the drawings.

It is further desirable that means be provided for preventing reverse turning of the 5 nose-piece 3, on its threads, and whereby, after being turned fully homeward, the same would become loosened from the main cylinder 2; and to this end I provide the casing 2 with a key-opening 26, the same being 10 formed in the wall of said cylinder, extending from the front end thereof somewhat rearwardly and downwardly with respect thereto, and intersecting at its inner portion the plane of the threads of said nose-piece, 15 said opening serving to receive a key 27, which binds at its inner end on one or more of the threads of said nose-piece, all as clearly illustrated in Fig. 2. Again, under the shocks imparted to the shank 24, in the 20 practical operation of the device as a whole, said key might occasionally become loosened, and to insure a binding effect thereby, even under this condition thereof, on the threads of 25 said nose-piece, and in any event a due adjustment, at all times, of the latter with respect to the cylinder 2, I provide an elastic connection 28, here shown as taking the form of a spiral spring, the same being attached at one of its ends to the protruding or outer end of 30 the key 27, extending therefrom partially around the nose-piece 3, and connected, in any appropriate manner, as through the medium of a pin 29, to the said nose-piece, at any point desired circumferentially thereof, and tending 35 at all times to exert an elastic force thereon in the direction to turn the same homeward. Observing now, and which should be clearly apparent from the foregoing description of my improved device, that the striking-piston 40 aforementioned is self-acting in controlling the respective inlet-ports and the respective exhaust ports, in the manner hereinbefore stated, the operation of the device may be described as follows: The piston having assumed, say, the position indicated in Fig. 1, a suitable power-medium, preferably air under pressure, is admitted to the distribution-chamber 6, by way of the main supply- 45 passage 5 and nozzle 4, from which distribution-chamber said power-medium gains entrance, by way of primary inlet-port 8, which is now open, into the expansion chambers 13 and 14, by way of the passage, as 15 and its 50 branch or branches 16, whereby communication is had between said chambers 13 and 14, said power-medium practically entering both of said chambers simultaneously by reason of its pressure; whereupon it simultaneously acts on both of the faces 30 and 31, of the 55 heads 11 and 12, respectively, and powerfully, by reason of the increased effective area which the combined faces 30, 31, present thereto, thrusts said piston forward, thereby causing its striker 23 to accordingly strike 60 and deliver a powerful blow to, any suitable

object, as the tool-shank 24. The piston now having assumed the position indicated in Fig. 2, and chambers 13 and 14 having been accordingly exhausted, as by way of the primary exhaust port 18, which is now open, 70 the power-medium gains entrance to the secondary chamber 17, by way of secondary inlet-port 9, which is now open; whereupon it acts on the inner face of the piston-head 12, thereby returning said piston to the position 75 indicated in Fig. 1, the effective area of the face last referred to being of sufficient area for this purpose. Secondary exhaust being now open, that is, the exhaust port denoted by the numeral 19, the chamber 17 is exhausted, and said piston is in readiness for another thrust forward, in the manner first above described, and so on, the striking-piston reciprocating with great rapidity, and the power-medium being accordingly admitted 80 into and exhausted from the respective chambers 13, 14 and 17.

It will be seen that my present improved pneumatic tool is particularly well adapted for the purposes for which it is intended, and 90 further that the same may be modified to a considerable extent, particularly as regards the location of the passage whereby communication is established between the respective chambers 13 and 14, and other details of 95 the general construction, without materially departing from the spirit and principle of my invention.

Having thus fully described my invention, what I claim and desire to secure by Letters 100 Patent is:

1. A device of the class herein described comprising a main cylinder, a subsidiary cylinder therein and forming circumferentially therewith a power-medium distribution-chamber, said main cylinder having a supply-passage communicating with said distribution-chamber, and primary and secondary exhaust ports, primary and secondary inlet-ports, whereby communication is established between said distribution-chamber and the interior of said main cylinder, and a compound, striking-piston, the latter reciprocating within said main cylinder, and controlling the inlet-ports alternately, the exhaust ports alternately, and the inlet-ports inversely to the exhaust ports, substantially as herein specified.

2. A device of the class herein described comprising a main cylinder; a subsidiary cylinder therein and forming circumferentially therewith a distribution-chamber, said main cylinder having a supply-passage communicating with said distribution-chamber; a striking-piston, the same reciprocating 120 within the main cylinder and having a medial valve-shoulder, working within said subsidiary cylinder, and working-heads at opposite sides of said valve-shoulder, said heads operating respectively within the bore of the main 125

130

cylinder and forming expansion chambers, one at the rear of each of said heads, said chambers being at all times in communication each with the other; an inlet-port whereby communication is established between said distribution-chamber and said communicating expansion chambers, said inlet-port being controlled by said valve-shoulder; and an exhaust port, whereby said communicating expansion chambers are exhausted, said exhaust port being controlled by one of the heads of said piston, alternately with the control of said inlet-port by said valve-shoulder, substantially as herein specified.

15 3. A device of the class herein described comprising a main cylinder; a subsidiary cylinder therein and forming circumferentially therewith a distribution-chamber, said main cylinder having a supply-passage communicating with said distribution-chamber; a striking-piston, the same having a medial valve-shoulder, working within said subsidiary cylinder, and a head, the latter working within the bore of the main cylinder and forming at the front face thereof a secondary expansion chamber; an inlet-port, whereby communication between said distribution-chamber and said secondary expansion chamber is established, said inlet-port being controlled by said valve-shoulder; and an exhaust port, whereby said secondary expansion chamber is exhausted, said exhaust port being controlled by said piston-head alternately with the control of said inlet-port by said valve-shoulder, substantially as herein specified.

30 4. A device of the class herein described comprising a main cylinder; a segmental, subsidiary cylinder therein and forming circumferentially therewith a distribution-chamber, said main cylinder being provided with a supply passage communicating with said distribution-chamber, and provided with one or more inlet-ports, whereby communica-

cation is established between said distribution-chamber and the interior of said main cylinder, the latter being provided with suitable exhaust ports; and a compound, striking-piston, the latter reciprocating within said main cylinder and said subsidiary cylinder, and being self-acting in controlling said inlet-ports, substantially as herein specified. 45

5. A device of the class herein described comprising a main cylinder; a subsidiary cylinder therein, said subsidiary cylinder being cut away circumferentially to form with the adjacent interior wall of said main cylinder, a power-medium distribution chamber, and being provided with primary and secondary inlet-ports whereby communication 50 is established between said distribution chamber and the interior of said main cylinder, the latter being provided with a power-medium passage communicating with said distribution chamber; and a compound striking-piston, the latter reciprocating within said main cylinder and the subsidiary cylinder, and being self-acting in controlling said primary and said secondary inlet-ports, substantially as herein specified. 55

6. A device of the class herein described comprising a main cylinder having its bore threaded at the forward end thereof; a nose-piece, threaded and engaging the threads in the bore of said cylinder, the latter being provided with an opening intersecting the plane of the threads of said nose-piece; a key, inserted in said opening and firmly engaging the threaded portion of said nose-piece; and an elastic connection, the same engaging said 60 key and said nose-piece and thereby preventing reverse action of the latter on its threads, substantially as herein specified. 70
